UNITED STATES PATENT OFFICE.

WILLIAM H. ROWE, OF LOS ANGELES, CALIFORNIA.

VENDING MACHINE.

Application filed August 17, 1925. Serial No. 50,603.

This invention relates to vending machines.

The general object of the invention is to provide an improved coin actuated vending machine.

One of the specific objects of the invention is to provide an improved coin actuated plunger for use in vending machines.

Another object of the invention is to provide a novel form of fraud prevention mechanism for use with coin actuated machines.

A further object of the invention is to provide an improved coin receptacle which is particularly adapted for use with coin actuated vending machines.

Another object of the invention is to provide a coin actuated mechanism wherein the coin or coins used by the purchaser are in full view and remain in view until another purchase is made and other coins are deposited.

Other objects of the invention will be apparent from the following description taken in connection with the accompanying drawings, wherein:

Fig. 1 is a central sectional view partly in elevation showing one embodiment of my invention;

Fig. 2 is a section on line 2—2, Fig. 1;
Fig. 3 is a front elevation showing the cabinet;

Fig. 4 is a section on line 4—4, Fig. 2;
Fig. 5 is a section on line 5—5, Fig. 1;
Fig. 6 is a section on line 6—6, Fig. 5;

Fig. 7 is a fragmentary detail in elevation, and

Fig. 8 is a wiring diagram.

Referring to the drawing by reference characters, I have shown a cabinet at 10. This cabinet includes a base 11 having a back 12 fitted thereto. The cabinet is provided with a shelf 14 which has a plurality of coin slots 15 therein.

The cabinet is provided with a front 16 below the shelf and a front portion 17 above the shelf. The front portion 17 comprises a removable closure the lower part 18 of which is adapted to fit between lugs 19 to prevent its removal while the upper portion 50 abuts against a rib 20 and is held in place by the bolt 21 of a lock 22.

The closure 17 allows access to the storage compartments 23 in which the packages to be vended, shown as packages of cigarettes 24, are arranged. The compartments

are defined by partitions 25 which have horizontal base flanges 26 extending part of the length thereof. These base flanges serve as supports for the cigarette packages.

The lower front portion 16 is provided with a removable cover 27 which has tongues 28 thereon which fit behind the front portion of the cover 16. The other end of the cover 27 is provided with a lock 28' the bolts 29 of which fit behind the cover 16 and serve to hold the closure in place. The closure is provided with a glass panel 30 for a purpose to be presently described.

One end of the cabinet has a closure 31 therein which is held in place by a locking bolt 32.

The coin released plungers are indicated generally at 35. These plungers have cylindrical end portions which pass through apertures 36 in the front portions 16. The plungers are provided with rectangular portions 37 which are notched as at 38. Each plunger is mounted in a U-shaped case 40 which has flanges 41 thereon shown as secured between lugs 42 on the shelf 14. They may be held in place in any desired manner. Each case 40 is provided with a transverse pin 44 which limits the movement of the plunger in one direction by engagement with the shoulder at one end of the notch 38.

The other shoulder indicated at 45 in Fig. 1 is adapted to engage the end faces 46 of a pair of dogs 47 which are pivoted at 48 to the case. The construction is such that normally the plunger has but little movement on account of its engagement with the faces 46 of the dogs 47.

Each plunger adjacent the shoulder 45 is provided on each face with a notch 50 which in conjunction with the adjacent wall of the casing 40 forms a coin slot 51. These coin slots 51 are disposed beneath the coin slots 15 in the shelf 14.

My invention is particularly applicable for use where it is necessary to insert two coins of different value in order to affect operation of the machine and the size of the slots 15 and 51 will be determined by the size of coin required to operate the machine.

Each of the dogs 47 is provided with a cut away part 53 which has an inclined surface 54. When the proper coin is inserted in each slot and the plunger 35 is pressed inwardly the coins will engage the surfaces 54.

and will rock the dogs 47 upwardly as the plunger moves in so that the faces 46 clear the shoulders 45 whereby the plunger may advance.

5 The locking dogs 47 are provided with a cutaway portion 56 which has an inclined part 57 thereon. As the coin advances from the position shown in Fig. 6 the cutaway part 56 will be adjacent the coin so that 10 the locking dog will swing downwardly on its pivot until the inclined part 57 engages the coin and pushes it out of the coin slot 51. The case 40 is provided with apertures 58 therein and through these apertures the 15 coins are discharged into a chute 60 which has side walls 61.

In Fig. 5, at 59, I show coins which are being engaged by the inclined portions 57 to be discharged into the coin chute 60.

20 The coin chute is provided with bottom walls 62 which converge downwardly and forwardly to a discharge opening 63 which is disposed adjacent to and above a coin box 64 to be later described.

25 One of the converging walls 62 has a curved horse shoe magnet 65 secured thereto. This magnet is arranged over a lug 66 from which it is insulated and is secured in place by means of a cross bar 67 which is 30 held in place by means of a screw 68.

The low poles 70 of the magnet are arranged in a recess in the wall 62 on which the magnet is fixed and each pole is spaced from the adjacent wall.

35 The vending machine is provided with a battery 72 which has two leads 73 and 74 extending therefrom. The lead 74, as shown in Fig. 1, includes a switch 75 and an electric bell 76. The lead 73 is secured to the 40 wall 62 while the lead 74 is secured to the magnet 65. As the objects fed to the machine pass down the coin chute to the discharge chute 63 some part of the objects will engage the pole of the magnet or will 45 come so close to the pole that it will be attracted to it if the object is made of iron or steel.

The magnet will thus hold an iron or steel slug in position so that the space between 50 the pole of the magnet and the wall 62 will be bridged to thereby close the circuit and sound the alarm bell 76 while a proper coin will pass the magnet after momentarily closing the circuit. To dispose of a slug attracted by the magnet the switch 75 will be 55 operated to break the circuit to the magnet thus allowing the slug to fall to the coin box.

The coin box 64 previously mentioned is 60 shown as rectangular in shape and as provided with sides 77 and end walls 78. The end walls are provided with flanges 80 which receive a sliding bottom 81 which has a flange 82 thereon. The coin box is disposed in the rear of the door 27 so that when

this door 27 is removed the flange 82 may be grasped and the closure 81 pulled forwardly so that the coins will drop onto the discharge chute 83 down which the packages 24 slide when freed by the plunger. 70

The end walls 78 are extended upwardly as shown at 84 and are apertured as at 85 for the reception of a pintle 86. Upon this pintle a pair of closure flaps 87 are mounted. The ends 78 are provided with angle members 88 and when the pintle 86 is raised the closure flaps will swing inwardly as shown in Fig. 4. When the pintle 86 is lowered the closure flaps 87 will move to closed position, as shown in Fig. 1, by sliding along 80 the angle members 88.

In order to lift the pintle members, I mount a pair of arms 90 fixedly upon a shaft 91 which is mounted on bearings 92 within the casing. Each arm is provided with a 85 forked end 93 which fits over the pintle 86 so that as the arm 90 is rocked the pintle will be raised and lowered to operate the closure flaps 87.

In order to rock the shaft 91 I fix upon 90 this shaft a plurality of arms 95 which are adapted to be engaged by pivoted dogs 96 one of which is mounted on the end of each plunger 37 in a recess 97. The construction is such that as each plunger moves inwardly 95 the lower portion of the dog 96 will engage an arm 95 and will rock this arm momentarily to quickly raise the closure flaps.

As soon as an arm 95 clears its dog 96 it will move back to normal position so that 100 the closure flaps will be closed before the curved part 57 ejects the coins from the coin slots. As a result of this arrangement the coins will fall upon the top of the coin box and will remain there to be viewed 105 through the glass panel 30 until the machine is again operated.

From the foregoing description it will be apparent that the coins used to operate the machine will pass at once to a position where 110 they can be viewed and that the coins will remain in view until the machine is again actuated.

On each plunger opposite the recesses 97 I arrange recesses 100 and in these recesses 115 I pivot a dog 101 the upper ends 102 of which will engage the packages of cigarettes as the plungers move forward to force the packages along the base flanges 26 until the package of cigarettes is freed and the superimposed cigarettes are allowed to move 120 downwardly.

As the plunger moves rearwardly the dog 101 will assume the dotted line position shown in Fig. 6 and will idly move beneath 125 the lowermost package of cigarettes without disturbing them. It will be understood that the dogs 101 are out of alignment with the arms 95.

The dogs 101 have their lower portion of 130

considerable weight so that when released they will normally assume a vertical position as shown in Fig. 1.

In order to return the plunger to a normal position after a package has been released, I arrange a lug 110 upon each casing 40 and another lug 111 upon each plunger. These lugs are connected by springs 112 so that when freed each plunger will move to the position shown in Fig. 1. Each casing is recessed as shown at 114 to accommodate a lug 111.

If a coin which is too small to operate the coin release mechanism is inserted in the slot 15, it will pass through this slot and through the slot 51 and will strike a deflecting member 115 which is arranged above the coin box 64. This member 115 has inclined sides so that coins falling thereon will be deflected beyond the ends of the coin box and will fall down and strike the curved wall of the discharge chute 83 so that it can be recovered by the person using them.

From the foregoing description it will be apparent that I have invented a coin actuated mechanism which is highly efficient and which can be economically manufactured and that when a steel or iron slug is introduced it will sound an alarm. Moreover the coins used in operating the mechanism will remain in view until it is again operated.

I preferably place a plate 120 as shown particularly in Fig. 1, where it will serve to prevent a person from tampering with the operating mechanism.

Having thus described my invention, I claim:

1. In a coin controlled mechanism, a casing, a coin released plunger, a coin box, means to direct coin to said coin box, a pintle mounted adjacent to said box, a cover hinged to said pintle, and adapted when in one position to close the coin box, means to raise and lower said pintle to open and close the coin box, and other means operable on movement of said plunger in one direction to actuate said raising and lowering means to cause said pintle to move to raise the cover and cause coins thereon to drop into said coin box.

2. In a vending machine, a case for goods to be vended, a delivery plunger, coin freed mechanism associated with said plunger, a separate coin box, said box having a closure thereon, said closure comprising two members hinged together, means to operate the closure, means to deliver coins upon said closure, and means whereby the operation of the plunger will cause said closure to move to cause coins thereon to be deposited in the box after which the closure will move to closed position to receive other coins thereon.

3. In a coin actuated mechanism, a coin receptacle comprising a box having a bot-

tom and having a top thereon, said top comprising two members hinged on a common pintle disposed above the top of the box, a coin chute leading to the top of the box, a coin freed plunger, and means whereby upon the insertion of a coin and the actuation of the plunger said pintle will first be raised to allow the coins on the box to be dropped into the box after which the pintle will be lowered to close the receptacle so that the last used coin will be deposited upon the top of the box.

4. In a coin controlled mechanism, a casing, a coin released plunger, a coin box, a discharge chute for coins, said coin box being disposed beneath said chute, said box having wings at each end thereof, an aperture in each wing, a pintle movable in the apertures, a cover hinged to said pintle, and adapted when in one position to close the money box, a rock shaft in said casing, an arm on said shaft, said arm engaging said pintle and being adapted to raise and lower it, and means operated by movement of said plunger in one direction to raise the cover.

5. In a coin controlled mechanism, a casing, a coin released plunger, a coin box, a discharge chute for coins, said coin box being disposed beneath said chute and having a bottom and having wings at each end thereof, an aperture in each end wing, a pintle movable in the apertures, a cover hinged to said pintle, and adapted when in one position to close the money box, a rock shaft in said casing, an arm on said shaft, said arm engaging said pintle and being adapted to raise and lower it, a pivoted dog on said plunger and means operable on movement of said plunger in one direction for causing said dog to rock said shaft and said arm to thereby raise the cover to cause coins thereon to drop into said coin box, said plunger having coin slots therein and means to discharge coins from the coin slots after the coin box covers have been raised and lowered.

6. In a device of the class described, a casing, a coin released plunger, a coin box, a discharge chute for coins, said coin box being disposed beneath said chute and having a bottom and having wings at each end thereof, an aperture in each end wing, a pintle movable in the apertures, a cover supported by said pintle, and adapted when in one position to close the money box, a rock shaft in said casing, arms on said rock shaft, said arms engaging said pintle and being adapted to raise and lower it, another arm on said rock shaft, said other arm being associated with said coin released plunger, a pivoted dog on said plunger adjacent to said other arm and means whereby movement of said plunger in one direction will cause said

dog to rock said shaft and said first mentioned arms to thereby raise the cover to cause coins thereon to drop into said coin box, said plunger having coin slots therein and means to discharge coins from the coin slots after the coin box cover has been raised and lowered.

7. In a coin controlled mechanism, a casing, a coin released plunger, a coin box, a discharge chute for coins, said chute having a curved wall at one side, said coin box being disposed beneath said chute and having a bottom and having wings at each end thereof, an aperture in each end wing, a pintle movable in the apertures, a pair of cover members hinged to said pintle, and adapted when in one position to close the money box, said pintle projecting beyond the ends of said box, a rock shaft in said casing, arms on said rock shaft, said arms engaging said pintle and being adapted to raise and lower it, an other arm on said rock shaft, said other arm being associated with said coin released plunger, a pivoted dog on said plunger adjacent to said other arm and means whereby movement of said plunger in one direction will cause said dog to rock said shaft and said first mentioned arms to thereby raise the covers to cause coins thereon to drop into said coin box after

which said covers will close, said plunger having coin slots therein and means to discharge coins from the coin slots after the coin box covers have been raised and lowered.

35

8. In a coin actuated mechanism, a casing, a coin receptacle comprising a box, means to deliver coins to said box, said casing having an aperture therein, a removable closure for said aperture, said box having a removable bottom, said removable bottom being arranged adjacent to said removable closure and means whereby said bottom is held immovable by said closure when said closure is in an operative position.

45

9. In a coin controlled mechanism, a casing, a coin box in said casing, means to direct a coin to said coin box, said coin box having a bottom and having a wing at each end thereof, an aperture in each wing, a pintle movable in the apertures, a pair of cover members hinged to said pintle and means to move said pintle, said pintle in one position holding said cover members in closing position and said pintle when in another position holding said cover members in open position.

50

In testimony whereof, I hereunto affix my signature.

WILLIAM H. ROWE.
